RAIL-BOND.

No. 802,463.

Specification of Letters Patent.

Patented Oct. 24, 1905.

Application filed December 22, 1904. Serial No. 237,868.

To all whom it may concern:

Be it known that we, GEORGE A. MEAD and CHARLES R. STURDEVANT, citizens of the United States, residing at Mansfield, in the 5 county of Richland and State of Ohio, have invented a new and useful Improvement in Rail-Bonds, of which the following is a specification.

This invention relates to rail-bonds.

10 The object of the invention is to provide a rail-bond of such construction, especially at the terminals thereof, which are applied to the rail or other part to be bonded, as to avoid being knocked or torn from the rail by accidental contact with wheels or the feet of horses or the like passing along the street.

15 A further object of the invention is to provide a rail-bond having a terminal arranged to present a sharpened or knife edge toward the tread-surface of the rail to which the bond is to be applied.

20 Other objects of the invention will appear more fully hereinafter.

The invention consists, substantially, in the 25 construction, combination, location, and arrangement of parts, all as will be more fully hereinafter set forth, as shown in the accompanying drawings, and finally pointed out in the appended claims.

30 Referring to the accompanying drawings and to the various views and reference-signs appearing thereon. Figure 1 is a view in side elevation of a rail-bond constructed in accordance with the principles of our invention. Fig.

35 2 is a similar view of a different form of bond embodying the principles of our invention. Fig. 3 is a broken view, in transverse section, showing the application to a rail of a bond embodying the principles of our invention. Figs.

40 4, 5, 6, 7, 8, and 9 are views in transverse section of various forms of bond-terminals embraced within the spirit and scope of our invention. Fig. 10 is a top edge view of the form of bond-terminal shown in Fig. 7. Fig. 11 is a

45 view in front elevation of the form of bond-terminal shown in transverse section in Fig. 8. Fig. 12 is a view similar to Fig. 11, showing the form of bond-terminal illustrated in cross-section in Fig. 6. Fig. 13 is a top edge view 50 of the bond-terminal shown in Fig. 12. Fig.

Fig. 14 is a view in side elevation of a form of bond-terminal having sharpened edges and ends of the type shown in Fig. 2. Fig. 15 is a similar view showing a different form of

bond-terminal of the type shown in Fig. 2. Fig. 16 is a top edge view of the form of terminal shown in Fig. 15. Fig. 17 is a broken view in section on the line *a a*, Fig. 15.

In the use of rail-bonds for bonding street-car rails, especially such rails as are employed in streets over which vehicles, carriages, pedestrians, or the like travel and where the bond-terminal is soldered or otherwise secured to the side surface of the rail-tread, it frequently happens that a wheel of a carriage, wagon, or the like, or the foot of a horse, &c., in passing over the rail comes in contact with or strikes the upper edge of the bond-terminal and tears it loose from its connection to or with the rail, thereby seriously interfering with and impairing the bond connection of the road or of the rails to each other. It is among the special purposes of our present invention to avoid this difficulty, while at the same time providing a sufficient bearing-surface for attachment of the bond-terminal to the rail.

In carrying out our invention we propose to so form the bond-terminal as that when it is applied to the side surface of the rail-tread in the ordinary manner and soldered or otherwise affixed thereto it will present a knife or sharpened edge upwardly or toward the tread-surface of the rail and with a flattened surface to be applied to the rail, so as to afford ample area of contacting surface for application of the terminal to the side of the rail-tread surface. In this manner we avoid the objection of all the terminal presenting an enlarged or squared upper surface where it is liable to be struck and torn loose from its fastening to the rail by a wheel or the hoof of a horse or other animal passing along the roadway, the sharpened or thin upper edge of the bond-terminal presenting a comparatively little, or practically no, surface which would be liable to be struck by a wheel, hoof, or foot or to be torn loose from its attachment to the side surface of the rail-tread. This idea may be accomplished and carried out in many specifically different ways, and we have shown various forms of bond-terminals embodying the principles of our invention.

In the drawings reference-sign A designates a rail or other part to be bonded, B a portion of the ordinary fish-plate applied thereto, and C a form of rail-bond selected for the purposes of illustrating the practical application of our invention.

It is obvious that the particular form or type of bond is immaterial so long as it is provided with terminals for application flatwise against the surface to be bonded. For instance, in Fig. 1 we have shown a laminated bond C, having terminal feet D, the laminated body of the bond intermediate the feet being formed into loop shape. In Fig. 2 we have shown a form of bond the body portion E of which is laminated and formed into substantially U shape and having terminals F extending transversely across the ends of the body portion. In practice we prefer to form the bond-terminals of solid homogeneous masses, though we do not desire to be limited in this respect. In the form of terminal shown in Figs. 1 and 2 said terminals are of substantially wedge shape in cross-section, as shown in Fig. 3, the outlines or bounding-surfaces of the bond-terminal in cross-section forming substantially a right-angled triangle, with its apex G presented toward and lying adjacent to the tread-surface of the rail and its hypotenuse forming the exterior surface of the terminal and one of its rectangular surfaces lying flatwise against the side surface of the rail-tread. By reason of this construction the bond-terminal presents a knife-edge upwardly-lying against the side surface of the rail-tread and its exterior surface forming in contour a continuation of the surface of the rail to which the bond is applied, thereby avoiding the formation of square shoulders or surfaces for a wheel, hoof, or foot to strike against, whereby the bond may be detached from its engagement with the rail. It is not necessary, however, that the bond-terminal be of triangular shape in cross-section. For instance, a terminal D' is shown in cross-section in Fig. 4, wherein the outer surface (indicated at H) is slightly concaved, the terminal, however, presenting a sharpened or knife edge G upwardly toward the tread-surface of the rail; and in Fig. 5 we have shown a terminal D'', presenting the sharpened or knife edge G' along its upper edge, but the outer surface H' thereof being convexed; and in Figs. 7 and 10 we have shown a bond-terminal D³, presenting a sharpened or knife edge G along the upper edge thereof, but beveled, as at H³, to form the sharpened edge G, the body of the terminal being generally of rectangular shape. In Figs. 8 and 11 we have shown a terminal D⁴ beveled to form an upper sharpened edge G and also a lower sharpened or beveled edge G', the outer surface of the bond being beveled both upwardly, as at H⁴, and downwardly, as at H⁴, leaving the inner surface of the terminal plane for application to the surface of the rail to be bonded, and this characteristic obtains throughout the various forms of our invention illustrated. In Fig. 9 we have shown a form of bond-terminal D⁵ in which both an upper and a lower sharpened edge G G' is formed; but the outer

surfaces H⁵ H⁶, which produce the sharpened edges G G', are concaved. In Figs. 6, 12, and 13 we have shown another form of bond-terminal D⁶, which is plano-convex in cross-section, thereby forming a sharpened upper edge G, as well as a sharpened lower edge G², the outer surface H⁷ of the terminal being convexed, while the inner surface of the terminal is plane for application against the surface to be bonded. In Figs. 15, 16, 75 and 17 we have shown the plano-convex form of terminal as applied to the terminals F' of the form of bond shown in Fig. 2, the outer surface of the terminal being convexed, while the inner surface is plane, thereby producing 80 a sharpened upper edge G. In Fig. 14 we have shown a terminal F² of the form shown in Fig. 2 and oppositely beveled, as in the form shown in Figs. 8 and 11, above described, to produce the sharpened upper edge G and also a 85 sharpened lower edge G'. If desired, and as illustrated in Figs. 10, 11, and 14, the ends of the terminals may also be beveled or sharpened, as indicated at J.

It will be observed that in the various forms 90 of terminals illustrated as exemplifications of our invention a flattened inner surface is produced to lie flatwise against the side surface of the rail-tread and that the upper edge of the terminal—that is, the edge presented toward the tread-surface of the rail—is reduced in thickness to a knife-edge, and these are 95 characteristic features of our invention.

It is obvious that many variations and 100 changes in the details of construction and arrangement would readily suggest themselves to persons skilled in the art and still fall within the spirit and scope of our invention. We desire it to be understood, therefore, that our 105 invention is not limited or restricted to the exact details shown and described.

We are aware that it is common practice to 110 bevel the edges of objects to avoid abrupt collision with other relatively moving bodies, and it may have heretofore been proposed to bevel rail-bonds for the purpose of adapting 115 them to their positions of use or to economize the metal; but such is not the equivalent of our invention, nor do we wish to claim the same, because in our invention the beveling 120 of the upper edge of the foot or terminal not only prevents it from coming into abrupt collision with moving bodies, but it causes the terminal or foot to stick more securely to the rail and renders it less liable to be ripped off 125 by a blow applied laterally to the side of the body portion. For illustration, should the terminal D receive a laterally-directed blow at its lower edge it would exert a tendency to rotate or tip on its lower inner corner, throwing the upper knife-edge outwardly, but the upper edge being considerably reduced in thickness and the rigidity of the terminal thereby greatly impaired it is 130 unable to exert sufficient force at its upper side

to rip the thin feather-like edge away from the grasp of the solder. When the terminal once starts to loosen at its upper edge, however, its entire security is destroyed, and it

5 would be thus started by a blow of the described character if made solid and rigid throughout its vertical extent.

Having now set forth the object and nature of our invention and various constructions 10 embodying the principles thereof, what we claim as new and useful and of our own invention, and desire to secure by Letters Patent, is—

1. The combination with a rail having a tread, of a bond provided with a terminal formed with a flattened surface for application against the side surface of the tread of the rail, and being reduced in thickness toward the edge thereof which is presented to 15 toward the tread-surface of the rail.

2. The combination with a rail having a

tread, of a bond provided with a terminal formed with a flattened surface beveled to the surface of the rail at its upper edge and being soldered to the rail.

25

3. The combination with a rail having a tread, of a rail-bond provided with a terminal formed with a flattened surface at its inner side and soldered to the rail, said terminal being beveled from its lower edge upwardly 30 to the surface of the rail, terminating in a thin knife-edge at its upper edge, and a flexible body portion at each end of which one of the described terminals is secured.

In witness whereof we have hereunto set our 35 hands, this 16th day of December, 1904, in the presence of the subscribing witnesses.

GEORGE A. MEAD.

CHARLES R. STURDEVANT.
